Primary Examiner — George D Kirschbaum*Assistant Examiner* — Cleso Moore, Jr.(74) *Attorney, Agent, or Firm* — Jeffrey S. Melcher; Manelli Selter PLLC(57) **CLAIM**

I claim the ornamental design for a profile to a worktable, as shown and described.

DESCRIPTION

FIG. 1 is a perspective view of a worktable;
FIG. 2 is a front view of the worktable;
FIG. 3 is a back view of the worktable;
FIG. 4 is a right side view of the worktable;
FIG. 5 is a left side view of the worktable;
FIG. 6 is a top view of a worktable; and,
FIG. 7 is a bottom view of a worktable.
